UNITED STATES PATENT OFFICE.

ULRICH HUGENTOBLER, OF UNION CITY, NEW JERSEY, ASSIGNOR TO CHARLES COMORA EMBROIDERY COMPANY, INC., OF WEEHAWKEN, NEW JERSEY, A CORPORATION OF NEW JERSEY.

DESIGN FOR A LACE MEDALLION.

Application filed July 31, 1928. Serial No. 27,642. Term of patent 7 years.

To all whom it may concern:

Be it known that I, ULRICH HUGENTOBLER, a citizen of the United States, residing at Union City, in the county of Hudson and State of New Jersey, have invented a new, original, and ornamental Design for Lace Medallion, of which the following is a specification, reference being had to the accompanying drawing, forming part thereof.

The figure is a plan view of a lace medallion, showing my new design, the broken line showing a continuation of the outline of the medallion illustrated in detail.

I claim:

The ornamental design for a lace medallion, as shown and described.

ULRICH HUGENTOBLER.
